UNITED STATES PATENT OFFICE.

RUSSELL H. WILHELM, OF EASTON, PENNSYLVANIA, ASSIGNOR TO INGERSOLL-RAND COMPANY, OF JERSEY CITY, NEW JERSEY, A CORPORATION OF NEW JERSEY.

BLOWING DEVICE.

Application filed January 29, 1927. Serial No. 164,478.

This invention relates to rock drills, but more particularly to a blowing device for fluid actuated rock drills of the hammer type.

The objects of the invention are to permit an uninterrupted supply of pressure fluid under full line pressure to flow through the device and the drill steel for removing the cuttings from the drill hole and to prevent reciprocation of the distributing valve and the piston during the blowing period. Other objects will appear hereinafter.

The invention is shown in one of its preferred forms in the accompanying drawings, in which

15 Figure 1 is a longitudinal sectional elevation of a rock drill showing the relative position of the moving parts when the piston is on its forward stroke;

20 Figure 2 is a view similar to that in Figure 1, showing the relative position of the moving parts when the piston is on its rearward stroke, and

25 Figure 3 is a view similar to Figures 1 and 2, showing the valve held inoperative in the valve chamber.

Referring to the drawings, a cylinder A of the rock drill is provided with a back head P, a front head G and a piston D. The piston D has a reduced striking end consisting of a 30 smooth cylindrical portion D' and a fluted shank O.

During the operation of the tool the piston D delivers blows of impact to a drill steel K which is secured in its operative position by 35 a chuck H which engages the shank J of the drill steel K. The interior surface of the chuck H is fluted as at L to cooperate with the fluted end O of the piston D. A front cylinder washer E forms a closure for the 40 front end of the cylinder A and acts as a guide to centralize the piston D.

Automatic rotation of the drill steel is provided by the usual rifle bar Q extending forwardly from a rotation washer Q' located in 45 a back head P, back head P forming a closure for the rear end of the cylinder A.

A valve chest S, mounted on the cylinder A and preferably formed integral therewith, is provided with a longitudinal bore T of uniform diameter throughout its length. A piston valve U having end heads W and V and a central head X is reciprocably mounted in

the bore T. Plugs Y and Z form closures for the rear and front ends respectively of the valve bore T and may be held in place in any 55 suitable manner.

In addition to forming a closure for the front end of the valve bore T, the plug Z has a forwardly extending portion d which is provided with a slot p at its forward end and a bore e centrally located and extending longitudinally of the plug. The bore e does not extend the full length of the plug, but connects with a smaller bore f thus forming a shoulder w.

Motive fluid is supplied to the drill at an inlet a from a source of supply (not shown). Motive fluid enters the cylinder A thru a passage b and the piston D is driven forward. At the same time spent motive fluid is exhausted from the front end of the cylinder thru a passage C and to the atmosphere by way of a suitable exhaust port x. When the advancing piston has uncovered a passage b' live pressure fluid is delivered to the face 75 W of the valve X and the valve is thrown rearwardly admitting pressure fluid to the passage C and thus driving the piston rearwardly. When the returning piston uncovers a passage c' the valve X is again thrown forwardly and live pressure fluid admitted to the rear end of the cylinder. This cycle of operations is continued indefinitely at the will of the operator.

It frequently becomes necessary during the 85 operation of drilling a hole to blow the hole free of rock chips and dust. To facilitate this blowing or cleaning operation the invention now to be described was devised.

When blowing the rock cuttings and dust 90 from the drilled hole it is necessary to hold the distributing valve X in its rearwardmost position to allow a free passage for the motive fluid from the inlet a thru the passage C into the cylinder A thru the flutes O and 95 into the passage v of the drill steel K.

To thrust and hold the valve X into the required position a lever r having a handle s and a cam portion t is rotably mounted on a pin q in the slot p. A plunger u extending 100 into the bore e is held in contact with the cam t by a spring o. The rearward end of the spring o seats against a piston or plunger head h in the bore e. The plunger head

h has a reduced, rearwardly extending portion *g* which fits slidably the bore *f*. Interposed between the rearward face of the plunger head *h* and the shoulder *w*, surrounding the plunger *g*, is a spring *k*.

Normally the plunger *g* is held out of contact with the valve *U* but when it becomes necessary to blow the drilled hole clear of dust and rock chips the operator pulls the lever or handle *s* rearwardly. By the action of the cam *t* the plunger *u* is forced into the bore *e*, the spring *o* is compressed and it in turn compresses the spring *k* behind the plunger head *h*. The plunger *g* being forced rearwardly contacts with the valve *U* and securely holds it in its rearward position permitting an uninterrupted supply of motive fluid to flow from the inlet *a* into the valve chamber *T*, thru the passage *C*, into the cylinder *A*, thru the flutes *O* and thru a bore *v* in the drill steel *K* into the drilled hole (not shown).

With the valve in the position last described the exhaust port *x* is covered in such a way that the motive fluid can only escape by way of the bore *v* in the drill steel *K*.

When the operator desires to stop the flow of pressure fluid to the drilled hole and resume the operation of drilling it is only necessary for him to push the lever *s* forwardly and the spring *k* will withdraw the plunger *g* from the face of the valve *U* and the valve

immediately begins its normal functioning.

I claim:

In a fluid actuated rock drill of the hammer type, the combination of a cylinder, a hammer piston in the cylinder having a reduced forward extension, a valve chest having a chamber, supply passages leading from the chamber to the ends of the cylinder, plugs forming closures for the ends of the chamber, a plunger slidable in one of the plugs, a pair of springs, one of said springs normally holding the plunger out of contact with the valve, the second spring normally in contact with said plunger, means for actuating the plunger to hold the valve immovable in the valve chest to permit an uninterrupted flow of pressure fluid from a source of supply through the said chamber and a supply passage and through one end of the cylinder to a hollow drill steel, said means comprising a cam, a lever attached to said cam, a plunger in contact with said cam, said second spring in contact with said second plunger, said second spring holding said second plunger in contact with said cam, said cam operable by means of said lever for forcing said second plunger into said plug and mechanically holding said first plunger in contact with said valve.

In testimony whereof I have signed this specification.

RUSSELL H. WILHELM.
